INVENTOR,

Alvin F. Warren

UNITED STATES PATENT OFFICE.

ALVA F. WARREN, OF PROVIDENCE, RHODE ISLAND.

DESIGN FOR AN ORNAMENTAL PIN.

SPECIFICATION forming part of Design No. 32,942, dated July 17, 1900.

Application filed May 31, 1900. Serial No. 18,671. Term of patent 7 years.

To all whom it may concern:

Be it known that I, ALVA F. WARREN, a citizen of the United States, residing at Providence, in the State of Rhode Island, have 5 invented and produced a new and original Design for an Ornamental Pin, of which the following is a specification, reference being had to the accompanying drawings, forming a part thereof.

6 In the drawings, Figure 1 represents a face view of the body of the pin, showing my new design. Fig. 2 represents a longitudinal section.

5 In the drawings, 1 represents the body portion of the ornamental safety-pin, 6 the pin-tongue, and 5 the safety-catch.

The new feature of my design consists in the shape of a leaf 1, upon the surface of which, within its boundary edges, are stamped the small leaves 2 and 3, with their stems crossing 20 each other.

It is apparent that this design is adapted for safety-pins, &c.

Having described my invention, what I claim as new, and desire to secure by Letters 25 Patent, is—

The design for an ornamental pin, as herein shown and described.

ALVA F. WARREN.

Witnesses:

ALVIN O. WARREN,
ANNIE E. WARREN.
